As herein shown, the head consists of sides A A', which are connected at their forward lower edges by a plate B, in the center of which is a stud or pin C', rising between the walls. The lower edges of the sides are cut away and the upper edges curved from the plate upward and rearward to the rear end, which is rounded. The rear ends are connected at the top and bottom, respectively, by a top D and bottom C, which, with the sides A A' and plate B, form a socket for supporting the arms of clothes-frames. In the top D and bottom C are alined openings a b, all as shown in the accompanying illustration.
